CLAIM

The ornamental design for a detergent box, as shown and described.

DESCRIPTION

1. Detergent box
- 1.1 Front
- 1.2 Back
- 1.3 Left
- 1.4 Right
- 1.5 Top
- 1.6 Bottom
- 1.7 Perspective
- 1.8 Perspective

(Continued)

The broken lines depict portions of the detergent box that form no part of the claimed design. The shade lines in the figures show contour and not surface ornamentation.

1 Claim, 8 Drawing Sheets
